(57) **CLAIM**

The ornamental design for a patient support system, as shown and described.

DESCRIPTION

FIG. 1 is a top, front, right side, perspective view of a patient support system;

FIG. 2 is a bottom, rear, left side, perspective view thereof;

FIG. 3 is a front view thereof;

FIG. 4 is a rear view thereof;

FIG. 5 is a right side view thereof;

FIG. 6 is a left side view thereof;

FIG. 7 is a top view thereof; and,

FIG. 8 is a bottom view thereof.

In the drawings, the broken lines represent unclaimed portions of the patient support system and form no part of the claimed design.

1 Claim, 7 Drawing Sheets
